INVENTOR

Harry A. Frank,
By *John, Burnt Hamilton*,
His Atty.

UNITED STATES PATENT OFFICE.

HARRY A. FRANK, OF TOLEDO, OHIO.

FOLDING TABLE.

1,240,964.

Specification of Letters Patent. Patented Sept. 25, 1917.

Application filed July 5, 1916. Serial No. 107,572.

To all whom it may concern:

Be it known that I, HARRY A. FRANK, a citizen of the United States, and a resident of Toledo, in the county of Lucas and State 5 of Ohio, have invented a certain new and useful Folding Table; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates to furniture, and particularly to tables of the folding or collapsing type.

The object of my invention is the provision, in connection more particularly with 20 light sewing and card tables having folding legs, of simple, efficient and improved means which is easily operable from an edge, of the table to simultaneously fold or unfold the several legs and to retain them in 25 either set-up or collapsed position.

The invention is fully described in the following specification, and while, in its broader aspect, it is capable of embodiment in numerous forms, a preferred embodiment 30 thereof is illustrated in the accompanying drawings, in which—

Figure 1 is a perspective view of a table embodying my invention in set-up position. Fig. 2 is a bottom plan view thereof in 35 folded position. Fig. 3 is an enlarged central cross-section of the table in set-up position, with parts broken away. Fig. 4 is an enlarged perspective view of the portion of the table through which the control lever 40 projects. Fig. 5 is a perspective view of the outer end of the control lever, and Fig. 6 is an enlarged sectional view of the leg carrying means of the table.

Referring to the drawings, 1 designates a 45 table top, which is preferably provided around the entire edge thereof with a depending flange 2. A leg 3 is pivoted at its inner end within each corner of the flange 2 being carried, in the present instance, by 50 a screw-pivot 4, which is projected through one leg of an L-shaped bracket member 5, thence through registering openings in the leg and a washer member 6, and threading at its inner end into a flange 2, as shown 55 in Fig. 6. It is thus evident that each

pivot-screw 4 is carried at one end by the respective bracket member 5 and at its other end by the table flange into which it threads and that the leg is retained in slightly spaced relation to the side flange with which 60 it is associated by the washer member 6. The pivots of successive legs are disposed at right angles to each other so that the legs are adapted to fold in the same direction perimetrically of the table edge or 65 flange.

A control lever 7 is pivoted to the under side of the table centrally thereof, as at 8, and has four radially projecting arms 9 disposed at right angles to each other and each 70 connected by a rod 10 to an adjacent leg 3 near the inner or pivoted end thereof, as at 11. One of the lever arms 9 is extended to form a handle and projects through a slot 12 in the adjacent flange side. The handle 75 arm of the lever is formed with a rib 13, which is adapted to engage with teeth 14 at one edge of the slot 12 to releasably retain the lever at the limit of its movement in either direction so that the legs may be 80 locked in either set-up or collapsed position.

It is evident that a turning of the lever 7 in one direction when the legs are in the folded or collapsed position shown in Fig. 2 will communicate an outward or unfolding 85 movement to all of the legs and will cooperate with the rods 10 to brace the legs in unfolded position. It is also evident that a movement of the lever in the opposite direction, when the legs are in unfolded position, will impart collapsing or folding movements thereto.

Each leg 3 is provided with a stop-finger 90 15, which is of L-form and secured thereto in position for its outwardly projecting finger to bear against the lower edge of the flange 2 when the leg is in full open position.

I wish it understood that my invention is not limited to any specific construction, arrangement or form of the parts, except in 100 so far as such limitations are specified in the claims.

Having thus described my invention, what I claim as new, and desire to secure by Letters Patent, is—

1. A table having a top portion of polygonal form, a set of legs hinged to different side edges of the table for folding and unfolding movements in the same direction perimetrically of the table, and means in- 110

cluding a lever member carried by the table top at its under side and connected to each leg, said means being operable when turned in one direction to impart simultaneous unfolding movements to the legs, and vice versa.

2. A table having a top, legs hinged to said top for folding and unfolding movements in the same directions perimetricaly
10 of the top, a lever pivoted to the under side of the table and having an arm for each leg, a rod connecting each lever arm to an adjacent leg near the inner end thereof, said lever and rods being operable upon a movement of the lever in one direction to impart

simultaneous unfolding movements to the legs, and vice versa.

3. A table having a top of square form and provided around its edge with a depending flange, a leg pivotally carried by the 20 flange in each angle thereof, and lever means pivoted to the under side of the table and having a plurality of arms, each connected to an adjacent leg and operable upon a movement of the lever in one direction to 25 impart simultaneous unfolding movements to the legs, and vice versa.

In testimony whereof I have hereunto signed my name to this specification.

HARRY A. FRANK.
